APPARATUS FOR STRETCHING AND GUIDING TUBULAR TEXTILE ARTICLES

Julien Dungler, Basel, Switzerland

Application January 14, 1950, Serial No. 138,684
In France April 15, 1949

23 Claims. (Cl. 26—55)

1

This invention relates to apparatus for treating, in particular guiding and stretching, pliable tubular objects or articles, more especially but not exclusively, tubular fabric material, such as knitted fabrics.

In installations for continuous processing or treating (dyeing, bleaching, sizing etc.) of fabrics it is generally desirable to feed the fabric from one stage (e. g. dyeing vat) to a subsequent stage (e. g. drier) by way of guide means, so as to insure that the diameter or width of the fabric when arriving at the last-mentioned stage be of a desired magnitude or predetermined value.

Difficulties have arisen in known installations of this character since due to the flexibility of the tubular fabric, external as well as internal guide means must be provided. Internal guide means, however, are not only difficult to mount and maintain in position, but become also quite inaccessible from without the fabric if it is desired to align or readjust the guide means.

The present invention avoids these and other difficulties and has as one of its primary objects the provision of means for guiding the fabric or other flexible, tubular article in such manner that the external and internal guide means work independently of each other.

More particularly, it is an object of this invention to provide in a machine or like system for continuously feeding flexible, tubular articles, means permitting adjustability of the guiding and stretching elements without necessitating interruption of the feed of the article whereby the ultimate width of the article at the location of the discharge end of the machine or like system may be controlled at will.

Another object of the instant invention is to provide novel and improved means for externally and internally guiding flexible, tubular articles while simultaneously imparting a positive feeding movement thereto.

In accordance with still another characteristic feature of the invention, the connecting line passing through the centers of adjacent two outer or external guide means is inclined with respect to the longitudinal axis of the tubular article in such manner that the latter becomes enlarged; the dimensions of the aforesaid outer or external guide means and of the inner ring means are so chosen that the tubular article leaves the stretching device with a considerably larger diameter than when the article was introduced into the stretching device.

Another feature of the invention resides in the provision of means forcing the inner ring means

2

against pairs of upper and lower rollers of which one pair is held in fixed position whereas the other pair is mounted for pivotal movement.

According to the invention, at least two stretching devices are mounted adjacent each other, the inner guide means of said devices being immovable and connected to each other by endless drive members, such as belts ensuring guidance of the tubular article along its path between the stretching devices.

These and other advantages, features and objects of the invention will become more evident from the ensuing description thereof and from the drawings attached thereto.

For a better understanding of the invention, reference is made to the accompanying drawings in which:

Fig. 1 is an elevational view of an apparatus made according to the invention, which apparatus is adapted to guide a tubular fabric (the fabric being omitted for sake of clarity).

Fig. 2 is a top plan view of the apparatus of Fig. 1, with the fabric shown as being transparent at the left-hand portion.

Fig. 3 is a fragmentary elevation, partly in section, of a modified apparatus according to the invention;

Fig. 4 is a somewhat schematic top plan view of essential parts of the left hand portion of the modified apparatus of Fig. 3; and

Fig. 5 is a schematic top plan view of an apparatus similar to that of Fig. 2 having incorporated additional features of Figs. 1 and 2.

Referring now more particularly to Figs. 1 and 2, there is shown a transverse support 1, which consists of a beam U-shaped in cross-section and open at the upper end thereof. Upon the support are slidably supported two carriages 2, 2^a. Each carriage has mounted thereon a pair of grooved guide pulleys 3, 4 and 3^a, 4^a, respectively, rotatable in a horizontal plane about vertical axes, the grooves of the pulleys being indicated at 5, 5^a. Fitting into these grooves are a pair of rings 6, 6^a, consisting of magnetic core material coated, or electrolytically applied thereto with a layer of copper or other non-oxidizable substance.

The two rings 6, 6^a are removably held in contact with the grooves of pulleys 3, 4 and 3^a, 4^a, respectively, by means of a pair of electromagnets 7, 7^a each of which being positioned intermediate the associated pair of pulleys and having its axis arranged to point substantially toward the center of the respective ring 6 or 6^a.

These electromagnets forming means are adapt-

ed to transmit their force to said rings. The spacing between these rings and the faces of the respective magnet cores 8, 8^a is such as to allow sufficient clearance for the passage of the fabric 9 whose incoming and outgoing portions are indicated at 9^a and 9^b, respectively.

It will be noted that the spacing of the axes of the pulleys 4, 4^a is less than that of the pulleys 3, 3^a which are positioned further along the path of the fabric 9, thereby resulting in the fabric being stretched as it advances.

It is desirable to position the rear pulleys 3, 3^a close to the line interconnecting the centers of the rings 6, 6^a, or slightly in back thereof as shown in Fig. 2, in order to insure that the fabric attain its greatest width substantially at the location of these rear pulleys; this will result in the fabric being positively guided externally as well as internally until it loses contact with the ring 6, 6^a without, however, causing any appreciable contraction of the fabric as it leaves the guiding apparatus.

In order to enable the apparatus to be further utilized as a means of advancing the fabric, at least one of the pulleys of each pair, say, 4, 4^a may be driven positively to rotate in a desired direction. In the embodiment illustrated, traction is imparted to the fabric 9 by positively rotating the pulleys 4, 4^a which for this purpose are provided on their shafts 104, 104^a with respective bevel gears 10, 10^a in mesh with similar gears 11, 11^a. The latter gears are keyed on or otherwise entrainable by a common shaft 13, journaled in bearings 12, 12^a which are supported from the carriages 2, 2^a by arms 112, 112^a, respectively. Shaft 13 is rotated continuously, over a chain-driven sprocket 14, from a suitable source of motive power (not shown) which may, if desired, be coupled with a drier or other apparatus of a subsequent stage to which the fabric is continuously supplied by the mechanism illustrated.

A threaded spindle 15 passes through nut members 16, 16^a which are respectively secured to the carriages 2, 2^a and mate with the lead screw portions 15^a, 15^b of this spindle, the two portions being threaded in opposite directions. A handwheel 17, secured to the spindle 15, may thus be used to vary the relative spacing of the two carriages and of the grooved pulleys carried thereon.

The operation of the apparatus is as follows:

After the carriages 2, 2^a have been shifted by means of the handwheel 17, to obtain the desired final diameter, the tubular fabric 9, in which the rings 6, 6^a have been inserted, is introduced into the apparatus in such manner that the two rings 6, 6^a are positioned adjacent their associated pulleys 3, 4 and 3^a, 4^a, respectively. The magnets 7, 7^a become thereupon energized, to thereby draw these two rings into meshing engagement with the grooves 5, 5^a of the pulleys with the fabric 9 interposed between the outer and inner rotating elements. Then, pulleys 4, 4^a are set in motion by means of the shaft 13, and the flattened tube 9 is thereby advanced so as to be distended or stretched when passing around the rings 6, 6^a. The distended fabric may then be fed to any desired piece of apparatus, such as a drier, which continuously takes up its outgoing portion 9^b.

It will be understood that the speed mechanism may be caused to be greater or less than the take-up speed in order to result in either a contraction or an elongation of the fabric in longitudinal direction. Longitudinal elongation may

also be effected by applying a braking force to the rear pulleys 3, 3^a.

It should be noted that adjustment of the distance between the pulleys 3, 3^a and 4, 4^a and also, thereby, between the rings 6, 6^a can be accomplished in a very easy manner, by merely rotating handwheel 17, regardless whether or not the machine is in operation.

Figs. 3 and 4 show a modification in that ring 6 is applied against rollers 3 and 4 by outer mechanical means in the form of a pair of inclined rollers 18, 19 providing an angle of approximately 60 degrees with respect to and transmitting a force against ring 6. The lower roller 18 is journaled in an invariable angular position on a support 20 which in turn is mounted on an arm 22 extending from carriage 2; the upper roller 19 is journaled on a similar support 21 which, however, is swingably held on a pin 24 on which it may be locked in any desired angular position, by means of a handle 25 whose extremity 125 threadedly engages the pin or stud 24, the latter forming a transverse projection on an arm 27 which in turn extends upwardly from the support 20, being thus fixed to the carriage 2. The rotatable mounting of the rollers 18, 19 on their respective supports may be effected by means of ball bearings 26 (one only being illustrated for the roller 18).

The rollers 18 and 19 are preferably made of an elastic material such as, for example, silicon rubber; it is, likewise possible to construct the ring 6 from elastic or light weight material which brings about considerable reduction of the weight of the rollers.

The embodiment illustrated in Figs. 3 and 4 functions essentially in the same manner as hereinabove set forth. To insert the fabric into the apparatus, however, the handle 25 is turned to loosen the swingable support 21, so that the roller 19 is raised to enable the fabric 9 with its internal guide ring 6 to be placed between the two rollers. Next the roller 19 is swung into contact with the inner surface of ring 6 (through the intermediary of the fabric), whereupon the handle 25 is operated to move support 21 about pin 24 and to lock the support 21 in predetermined operative position. From Fig. 4 it will be seen that the location of the rollers 18, 19 in respect to the pulleys 3, 4 is similar to that of the electromagnet 7 in Fig. 2, i. e. the axes of said rollers lie in a plane bisecting a line which interconnects the centers of these pulleys. The machine will be ready for operation as soon as the right-hand portion of the fabric (not shown in Figs. 3 and 4) has been inserted into the corresponding assembly of guiding elements which of course is identical with the assembly just described.

The ring 6 may be made of elastic material or 60 may be of tubular shape in order to reduce puckering of the fabric or material to a minimum.

While the arrangements illustrated in Figs. 2 and 4 cause the fabric to be distended along an arcuate path (represented by a portion of the periphery of each ring 6, 6^a), it is also possible in accordance with the invention to give this path a different configuration, e. g. a substantially linear one.

This is illustrated in Fig. 5 which shows, in 70 addition to the elements 3, 4, 6, 7 and 3^a, 4^a, 6^a, 7^a (already described in connection with Figs. 1 and 2), a set of similar elements 3^b, 4^b, 6^b, 7^b and 3^c, 4^c, 6^c, 7^c positioned forwardly of the former. The rings 6, 6^a and 6^b, 6^c are provided with peripheral grooves, such as 28 and 28^a, to accommodate

a pair of endless belts 29, 29a. Belt 29 interconnects the pulleys 6, 6b and forms, in combination therewith, the internal guide means for the left-hand portion of the fabric 9 as viewed in Fig. 5; belt 29a, similarly, interconnects the pulleys 6a, 6c and with them constitutes the internal guide means for the right-hand portion of the fabric.

On comparing the arrangement of Fig. 5 with that of Fig. 2 it will be seen that in Fig. 2 the folds 10 in the fabric were caused by the two pairs of pulleys 3, 3a and 4, 4a whereas in Fig. 5 the rear fold is due to the four pulleys 3, 4, 3a, 4a while the front fold is caused by the pulleys 3b, 4b, 3c and 4c. Accordingly, in the arrangement last 15 described, the first pair of rotary guide means previously referred to is constituted by the two sets of pulleys 3, 4 and 3a, 4a while the second pair is represented by the two sets 3b, 4b and 3c, 4c. Similarly, the two inner rotary guide means 20 in Fig. 5 are, respectively, the assembly 6, 6b, 29 and the assembly 6a, 6c, 29a.

It will be apparent that, inasmuch as the system last described may be arranged to cause a very gradual distension or enlargement of the 25 fabric 9, it may be preferable to systems using a single pair of inner rings 6, 6a whenever a fairly large proportional change in diameters is required.

While the rings 6b, 6c in Fig. 5 have been 30 shown of smaller diameter than the rings 6, 6a, it will be understood that these rings may be proportioned relative to one another in any desired manner suitable for the particular purpose contemplated.

From the foregoing it should be apparent that the invention is actually capable of overcoming the disadvantages of the prior art, initially referred to, and of accomplishing the various objects specifically set out. It will be seen that 40 all the embodiments described have in common the provision of an apparatus for guiding a flexible tubular object or article 9 including external guide means 3, 4, 3a, 4a, supporting means 2, 2a rotatably holding said external guide means in a fixed location, internal guide means 6, 6a freely 45 rotatable inside and engageable with the tubular object, and force transmitting means 1, 1a; 18, 19 positioned on said supporting means to exert upon said internal guide means, through said tubular object, a force urging said internal guide means toward said external guide means.

Furthermore, it should be understood that the invention is not limited to the specific embodiments described and illustrated but that it is, 55 on the contrary, capable of numerous modifications and adaptations without exceeding the scope of this disclosure. Thus, the position of the pulleys 3, 4 on their respective carriages may be made adjustable; also, a single support 1 may be designed to accommodate a plurality of guiding assemblies, each of the character hereinabove set forth for simultaneously guiding and/or feeding a plurality of tubular objects or articles passing alongside one another.

Various other variations will be readily apparent to persons skilled in the art and are intended to be embraced within the scope of the invention as defined in the appended claims.

Having thus described the invention, what is 70 claimed as new and desired to be secured by Letters Patent is:

1. An apparatus for guiding a flexible tubular object, comprising outer guide means, supporting means rotatably holding said outer guide means 75

in a fixed location, inner guide means for placement inside and for floating engagement with said tubular object, and means positioned on said supporting means and transmitting a force upon said inner guide means, through said tubular object and for urging said inner guide means toward said outer guide means.

2. An apparatus according to claim 1, wherein said outer guide means includes a pulley, and drive means for positively rotating said pulley.

3. An apparatus according to claim 1, wherein said outer guide means includes a pulley provided with a peripheral groove, said inner guide means including a peripheral portion fitting into and cooperable with said peripheral groove.

4. An apparatus according to claim 1, wherein said outer guide means includes a pair of pulleys lying in a common plane, each of said pulleys being provided with a peripheral groove, said inner guide means including a member having a peripheral portion fitting into the said groove of each of said pulleys.

5. An apparatus according to claim 1, wherein said force transmitting means includes a magnet, said inner guide means consisting at least in part of magnetic material.

6. An apparatus according to claim 1, wherein said force transmitting means includes a roller, said inner guide means comprising a ring having an inner annular surface engaged by said roller.

7. An apparatus according to claim 6, wherein said roller is rotatable in a plane inclined relative to the plane of said ring.

8. An apparatus for guiding a flexible tubular object, comprising a first pair of outer rotary guide means spaced apart in a direction transverse to the axis of said tubular object, feed means for advancing said tubular object in the direction of its axis, a second pair of outer rotary guide means positioned further away from and along the axis of said object, in the direction of its advance, and spaced apart in a direction transverse to the said axis, first and second inner rotary guide means freely rotatable inside said tubular object, first retaining means positioned to exert upon said first inner rotary guide means, through said tubular object, a force urging said first inner rotary guide means against one of each of said pairs of outer rotary guide means, and second retaining means positioned to exert upon said second inner rotary guide means, through said tubular object, a force urging said second inner rotary guide means against the other of each of said pairs of outer rotary guide means.

9. An apparatus according to claim 8, wherein said first retaining means is positioned intermediate said ones of each of said pairs of outer rotary guide means and said second retaining means is positioned intermediate said others of each of said pairs of outer rotary guide means.

10. An apparatus according to claim 8, comprising a first support for said ones of each of said pairs of outer rotary guide means, and a second support for said others of each of said pairs of outer rotary guide means, said first and second retaining means being mounted on said first and said second support, respectively.

11. An apparatus according to claim 10, comprising adjusting means for displacing said supports relative to each other.

12. An apparatus according to claim 8, wherein the spacing of said first pair of outer rotary guide means is less than the spacing of said second pair of outer rotary guide means.

13. An apparatus according to claim 8, wherein said feed means includes mechanism for positively rotating at least one of said pairs of outer rotary guide means.

14. An apparatus for guiding a flexible tubular object, comprising feed means for advancing said object in the direction of its axis, a first pair of pulleys arranged in a direction transverse to said axis, a second pair of pulleys positioned further along said axis and in the direction of advance of said object, and spaced apart in a direction transverse to said axis, the spacing of said second pair of pulleys being greater than the spacing of said first pair of pulleys, a first support having one of the pulleys of each of said pairs mounted thereon, a second support having the other of the pulleys of each of said pairs mounted thereon, a first and a second rotary member freely displaceable inside said tubular object, first retaining means on said first support positioned intermediate said ones of said pulleys to exert upon said first rotary member, through said tubular object, a force urging the periphery of said first rotary member against the peripheries of both of said ones of said pulleys, and second retaining means on said second support positioned intermediate said others of said pulleys to exert upon said second rotary member, through said tubular object, a force urging the periphery of said second rotary member against the peripheries of both of said others of said pulleys.

15. An apparatus according to claim 14, comprising an elongated base extending transversely to the axis of said tubular object, said supports being constituted by a pair of carriages slidably mounted on said base, and adjusting mechanism for relatively displacing said carriages in the direction of said base, thereby varying the spacing of said pairs of rollers.

16. An apparatus according to claim 14, wherein in each of said retaining means comprises a magnet, each of said rotary members consisting at least in part of magnetic material.

17. An apparatus according to claim 14, wherein in each of said retaining means comprises a roller, each of said rotary members comprising a ring having an inner annular surface engaged by said roller.

18. An apparatus according to claim 14, wherein all of said pulleys lie in a common substantially horizontal plane, each of said retaining means comprising a pair of rollers oppositely

inclined with respect to said plane, each of said rotary members comprising a ring having an inner annular surface engaged from above and from below, respectively, by said rollers.

19. An apparatus according to claim 18, wherein in each of said retaining means includes adjusting means for varying the inclination of at least one of said rollers.

20. An apparatus according to claim 14, wherein in both of said rotary members are of circular configuration.

21. An apparatus according to claim 14, wherein in each of said rotary members comprises a pair of circular elements each provided with a peripheral groove, and an endless belt engaging said grooves and coupling said circular elements together for simultaneous rotation.

22. An apparatus for guiding and feeding a lengthy flexible tubular object, comprising a first pair of outer rotary guide means spaced apart in a direction transverse to the longitudinal axis of said object, a second pair of outer rotary guide means spaced from said first pair of outer rotary guide means and from the longitudinal axis of said object, first and second inner rotary guide means for insertion inside said tubular object, and respective force transmitting means adapted to urge said inner rotary guide means against said outer rotary guide means and against said tubular object therebetween upon insertion of said inner rotary guide means in said tubular object, each of said force transmitting means having an axis intersecting with an axis interconnecting the centers of said inner rotary guide means.

23. An apparatus according to claim 22, wherein said force transmitting means are positioned between said pairs of outer rotary guide means, respectively.

40 JULIEN DUNGLER.
